SAFETY REMOVABLE FASTENER SLIDE

Barney Pruzan, New York, N. Y., assignor to
Ranger Fastener Corp., a corporation of New
York

Application August 24, 1935, Serial No. 37,705

12 Claims. (Cl. 24—205)

This invention relates to new and useful improvements in a safety removable fastener slide.

The invention has for an object the construction, of the post which holds the top and bottom trapezoidal guide plates spaced, with a vertical flat portion, a horizontal arrow shaped cam portion on an edge of said flat portion, a bottom rivet portion, and a top hook formed by a cut in the edge of said flat portion whereby the bottom rivet portion serves to hold the bottom trapezoidal guide plate flat against the bottom face of the horizontal arrow-shaped cam portion, and the top trapezoidal guide plate may be efficiently connected with the vertical flat portion. More particularly, the invention contemplates constructing the top horizontal guide plate with a slot engaging the flat portion and set flat against the top of said cam portion and having curled portions set against the sides of said flat portion and behind the cam portion.

A further object of the invention is the association of a latch element swivelly mounted on the top guide plate and engageable beneath said top hook to hold the guide plate down against the cam portion. It is proposed to construct this latch element with a hollow portion adapted to house a bent prong from a handle for the fastener slide which is pivotally mounted on the latch portion. With the arrangement, the bent prong is hid from view, and in a certain position of the handle engages the hooks of the fastener for latching the slide in a fixed position.

Still further the invention contemplates the provision of a prong formed upon the top trapezoidal guide plate, which limits pivoting of the latch element through a distance only sufficient to allow the operation of the latch.

Furthermore, the invention proposes a means for limiting the pivoting of the trapezoidal guide plates only through a distance sufficient to permit separation of the plates required for the removal thereof from the slide fastener.

Another object of the invention is the construction of a device as described which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a fragmentary plan view of a hook fastener with a slide according to this invention.

Fig. 2 is a plan view of a slide per se shown with the handle in the latching position.

Fig. 3 is an elevational view of Fig. 2, seen as 5 though looking in the direction of the line 3—3 of Fig. 2.

Fig. 4 is a sectional view taken on the line 4—4 of Fig. 2.

Fig. 5 is a horizontal sectional view on the line 10 5—5 of Fig. 3.

Fig. 6 is a horizontal sectional view on the line 6—6 of Fig. 3.

Fig. 7 is an elevational view looking in the direction of the line 7—7 of Fig. 3. 15

Fig. 8 is a sectional view taken on the line 8—8 of Fig. 2.

Fig. 9 is a perspective view of the fastener slide in open position.

Fig. 10 is a perspective view of the latch element per se illustrated upside down. 20

Fig. 11 is a perspective view of the latch element shown in Fig. 10, right side up.

Fig. 12 is a perspective view of the post used in the device. 25

Fig. 13 is a perspective view of the handle, per se.

Fig. 14 is a perspective view of the handle and the latch element, illustrated upside down.

Fig. 15 is a perspective view of the top trapezoidal guide plate per se. 30

Fig. 16 is a sectional view similar to Fig. 8 but illustrating a modified construction.

Fig. 17 is a fragmentary elevational view looking in the direction of the line 17—17 of Fig. 16. 35

In Fig. 1 a conventional hook fastener is illustrated comprising cloth strips 10 and 11 equipped with interengageable hooks 12 on their adjacent edges. A safety removable fastener slide is associated with these hook fasteners, 40 which slide is constructed according to this invention.

More particularly, the slide comprises a post 14 having a flat portion 14^a, an arrow shaped cam portion 14^b perpendicular to and extending 45 from an edge of said flat portion 14^a, a bottom rivet portion 14^c, and a top hook portion 14^d formed by a cut 15 in the edge of said flat portion 14^a. A bottom trapezoidal guide plate 16 for the hook fasteners 12 is set against the 50 bottom of said cam portion 14^b and is formed with an opening 17 set upon said rivet portion 14^c and rigidly held thereto by said rivet portion.

A top trapezoidal guide plate 19 for the hook fastener is formed with a slot 20 receiving said 55

flat portion 14^a and set against the top of said cam portion 14^b and having curled portions 19^a set against the sides of the flat portion 14^a and behind the cam portion 14^b . A pintle pin 21 passes through the curled portions 19^a and the flat portion 14^a for pivotally connecting these parts together. The top hook 14^d serves as a stop for limiting pivoting of the top trapezoidal guide plate 19 to the position illustrated in Fig. 9. In this position, the material of the guide plate strikes the hook.

A latch element 23 is swivelly mounted by a rivet 24 upon the top trapezoidal guide plate and is engageable beneath the top hook 14^d to hold the top guide plate down and against the cam portion. The latch element has its free end portion 23^a formed with a wedge surface (see Fig. 11) by which it is adapted to engage beneath the hook 14^d to accomplish the latching. A handle 25 is associated with the latch element by which the latter may be conveniently operated.

The handle 25 includes a transverse bar portion 25^a which engages beneath the latch element 23 and within edge recesses 26 (see Fig. 10) formed in the latch element. The latch element has a hollow protuberance 23^b in which a bent prong portion 27 from the bar 25^a is disposed. The protuberance 23^b normally hides the bent prong. In the position of the handle shown in Figs. 2, 3 and 8 the prong 27 is directed downwards, and when the slide is engaged on the hook fasteners 12 , engages between certain of the hooks to hold the slide in a fixed position. The handle 25 has an offset inner end 25^b which acts as a stop to limit pivoting of the handle to the position indicated by the dot and dash lines $25'$ in Fig. 3. In this position of the handle the prong 27 is disposed within the protuberance 23^b and the handle may be moved to pivot the latch element 23 , as indicated by the dot and dash lines $23'$ in Fig. 2. The guide plates may then be outwardly pivoted for removing the fastener slide. The element 23 is limited in its pivoting by a prong 28 projecting from the front edge of the guide plate 19 . The latch 23 has a corner 23^c thereof cut away which provides for the limited pivoting. This may be understood by an examination of Figs. 9 and 11. Fig. 14 illustrates the bent prong 27 disposed within the hollow protuberance 23^b .

In Figs. 15 and 16 another embodiment of the invention is disclosed which distinguishes from the previous form merely in the construction of the pivot for the latch. According to this form of the invention, the top trapezoidal guide plate is formed with a prong $28'$ having a projecting finger $28''$ bent downwards through an opening in the inner end of the latch to pivotally support the latch. Thus, the rivet 24 has been dispensed with. In other respects, this form of the invention is identical to the previous form and the parts thereof may be recognized by the same reference numerals.

The operation of the fastener slide may be understood by an inspection of Fig. 1. When the fastener slide is in this condition it may be moved towards the right to close the hook fasteners, or towards the left to open the hook fasteners. In either the closed or the open position of the hook fasteners the slide may be easily removed by forcing the handle 25 laterally to the position indicated by the dot and dash lines $25'$ in Fig. 2. The latch is then open and the trapezoidal top and bottom guide plates may

be pivoted apart a short distance to the position shown in Fig. 9. The fastener slide may then be removed and may be replaced in the reverse order to that necessary for its removal.

A feature of this invention resides in the construction of the post 14 and the parts associated with the post to produce a sturdy and efficient structure. The fact that the curled portions 19^a are disposed behind the base portions of the arrow shaped cam 14^b is important. Furthermore, the arrangement of the arrow shaped portion on the flat portion 14^a of the post and the arrangement of the rivet portion on the bottom thereof functions in obtaining the objects desired.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. In a safety removable hook fastener slide, a post having a flat portion, an arrow shaped cam portion perpendicular to and extending from an edge of said flat portion, a bottom rivet portion on said flat portion, a top hook formed by a slot in the edge of said flat portion, a bottom trapezoidal guide plate for the hook fastener set against the bottom of said cam portion and formed with an opening receiving said rivet portion and rigidly held in place by said rivet portion, a top trapezoidal guide plate for the hook fasteners and formed with a slot receiving said flat portion and set flat against the top of said cam portion and having curled portions set against the sides of said flat portion and behind the cam portion, a pintle pin received within said curled portions and passing through the flat portion for pivotally connecting these parts and a latch having a free end engaging said slot for adjustably holding said latch.

2. In a safety removable hook fastener slide, a post having a flat portion, an arrow shaped cam portion perpendicular to and extending from an edge of said flat portion, a bottom rivet portion on said flat portion, a top hook formed by a slot in the edge of said flat portion, a bottom trapezoidal guide plate for the hook fastener set against the bottom of said cam portion and formed with an opening receiving said rivet portion and rigidly held in place by said rivet portion, a top trapezoidal guide plate for the hook fasteners and formed with a slot receiving said flat portion and set flat against the top of said cam portion and having curled portions set against the sides of said flat portion and behind the cam portion, a pintle pin received within said curled portions and passing through the flat portion for pivotally connecting these parts, said top hook serving to limit pivoting of said top guide plate on said flat portion and a latch having a free end engaging said slot for adjustably holding said latch.

3. In a safety removable hook fastener slide, a post having a flat portion, an arrow shaped cam portion perpendicular to and extending from an edge of said flat portion, a bottom rivet portion on said flat portion, a top hook formed by a slot in the edge of said flat portion, a bottom trapezoidal guide plate for the hook fastener set against the bottom of said cam portion and

- formed with an opening receiving said rivet portion and rigidly held in place by said rivet portion, a top trapezoidal guide plate for the hook fasteners and formed with a slot receiving said 5 flat portion and set flat against the top of said cam portion and having curled portions set against the sides of said flat portion and behind the cam portion, a pintle pin received within said curled portions and passing through the 10 flat portion for pivotally connecting these parts, and a latch element swivelly mounted on said top guide plate and engageable beneath said top hook to hold said top guide plate down against said cam portion.
- 15 4. In a safety removable hook fastener slide, a post having a flat portion, an arrow shaped cam portion perpendicular to and extending from an edge of said flat portion, a bottom rivet portion on said flat portion, a top hook formed 20 by a slot in the edge of said flat portion, a bottom trapezoidal guide plate for the hook fastener set against the bottom of said cam portion and formed with an opening receiving said rivet portion and rigidly held in place by said rivet portion 25 25, a top trapezoidal guide plate for the hook fasteners and formed with a slot receiving said flat portion and set flat against the top of said cam portion and having curled portions set against the sides of said flat portion and behind 30 the cam portion, a pintle pin received within said curled portions and passing through the flat portion for pivotally connecting these parts, and a latch element swivelly mounted on said top guide plate and engageable beneath said top 35 hook to hold said top guide plate down against said cam portion, a handle associated with said latch element.
- 35 5. In a safety removable hook fastener slide, a post having a flat portion, an arrow shaped cam portion perpendicular to and extending from an edge of said flat portion, a bottom rivet portion on said flat portion, a top hook formed 40 by a slot in the edge of said flat portion, a bottom trapezoidal guide plate for the hook 45 fastener set against the bottom of said cam portion and formed with an opening receiving said rivet portion and rigidly held in place by said rivet portion, a top trapezoidal guide plate for the hook fasteners and formed with a slot receiving said flat portion and set flat 50 against the top of said cam portion and having curled portions set against the sides of said flat 55 portion and behind the cam portion, a pintle pin received within said curled portions and passing through the flat portion for pivotally connecting these parts, and a latch element swivelly mounted on said top guide plate and engageable beneath said top hook to hold said top guide plate down against said cam portion, and a handle having a transverse bar engaged beneath said latch 60 element through recesses therein, said transverse bar having a bent hook engageable with the hook fastener in a certain position of the handle, and said latch element having a hollow protuberance covering said bent hook. 40
- 60 6. In a safety removable hook fastener slide, a post having a flat portion, an arrow shaped cam portion perpendicular to and extending from an edge of said flat portion, a bottom rivet portion on said flat portion, a top hook formed 65 by a slot in the edge of said flat portion, a bottom trapezoidal guide plate for the hook fastener set against the bottom of said cam portion and formed with an opening receiving said rivet portion and rigidly held in place by said rivet portion, a top trapezoidal guide plate for the hook fastener set against the bottom of said cam portion 70 and formed with an opening receiving said rivet portion and rigidly held in place by said rivet portion, a top trapezoidal guide plate for the hook fasteners and formed with a slot receiving said flat portion and set flat against the top of said cam portion and having curled portions 75
- set against the sides of said flat portion and behind the cam portion, a pintle pin received within said curled portions and passing through the flat portion for pivotally connecting these parts, and a latch element swivelly mounted on said top guide plate and engageable beneath said top hook to hold said top guide plate down against said cam portion, and a handle having a transverse bar engaged beneath said latch element through recesses therein, said transverse bar having a bent hook engageable with the hook fastener in a certain position of the handle. 5
7. In a safety removable hook fastener slide, a post having a flat portion, an arrow shaped cam portion perpendicular to and extending from an edge of said flat portion, a bottom rivet portion on said flat portion, a top hook formed by a slot in the edge of said flat portion, a bottom trapezoidal guide plate for the hook fastener set against the bottom of said cam portion and formed with an opening receiving said rivet portion and rigidly held in place by said rivet portion, a top trapezoidal guide plate for the hook fasteners and formed with a slot receiving said flat portion and set flat against the top of said cam portion and having curled portions set against the sides of said flat portion and behind the cam portion, a pintle pin received within said curled portions and passing through the flat portion for pivotally connecting these parts, and a latch element swivelly mounted on said top guide plate and engageable beneath said top hook to hold said top guide plate down against said cam portion, and a handle having a transverse bar engaged beneath said latch element through recesses therein, said transverse bar having a bent hook engageable with the hook fastener in a certain position of the handle. 10
8. In a safety removable hook fastener slide, a post having a flat portion, an arrow shaped cam portion perpendicular to and extending from an edge of said flat portion, a bottom rivet portion on said flat portion, a top hook formed by a slot in the edge of said flat portion, a bottom trapezoidal guide plate for the hook fastener set against the bottom of said cam portion and formed with an opening receiving said rivet portion and rigidly held in place by said rivet portion, a top trapezoidal guide plate for the hook fasteners and formed with a slot receiving said flat portion and set flat against the top of said cam portion and having curled portions set against the sides of said flat portion and behind the cam portion, a pintle pin received within said curled portions and passing through the flat portion for pivotally connecting these parts, and a latch element swivelly mounted on said top guide plate and engageable beneath said top hook to hold said top guide plate down against said cam portion, and a handle having a transverse bar engaged beneath said latch element through recesses therein, said transverse bar having a bent hook engageable with the hook fastener in a certain position of the handle, said handle having its inner end offset to limit pivoting thereof. 15
9. In a safety removable hook fastener slide, a post having a vertical flat portion, a horizontal arrow shaped cam portion on an edge of said flat portion, a bottom rivet portion, a top hook formed by a cut in the edge of said flat portion, a bottom trapezoidal guide plate for the hook fastener set against the bottom of said cam portion and formed with an opening receiving said rivet portion and rigidly held in place by said rivet portion, a top trapezoidal guide plate for the hook fasteners and formed with a slot receiving said flat portion and set flat against the top of said cam portion and having curled portions 20

portion and formed with an opening set upon said rivet portion and rigidly held by said rivet portion, a top trapezoidal guide plate for the hook fasteners and formed with a slot receiving 5 said flat portion and set flat against the top of said cam portion and having curled portions set against the sides of said flat portion and behind the cam portion, a pindle pin received within said curled portions and passing through 10 the flat portion for pivotally connecting these parts, and a latch element swivelly mounted on said top guide plate and engageable beneath said top hook to hold said top guide plate down against said cam portion, and a handle having 15 a transverse bar engaged beneath said latch element through recesses therein, said transverse bar having a bent hook engageable with the hook fastener in a certain position of the handle, and means for limiting pivoting of said 20 latch element.

10. In a safety removable hook fastener slide, a post having a vertical flat portion, a horizontal arrow shaped cam portion on an edge of said flat portion, a bottom rivet portion, a top hook formed by a cut in the edge of said flat portion, a bottom trapezoidal guide plate for the hook fastener set against the bottom of said cam portion and formed with an opening set upon said rivet portion and rigidly held by said 25 rivet portion, a top trapezoidal guide plate for the hook fasteners and formed with a slot receiving said flat portion and set flat against the top of said cam portion and having curled portions set against the sides of said flat portion 30 and behind the cam portion, a pindle pin received within said curled portions and passing through the flat portion for pivotally connecting these parts, and a latch element swivelly mounted on said top guide plate and engageable beneath said top hook to hold said top guide plate down against said cam portion, the swivelling of said latch element being accomplished with a rivet engaged therethrough and through 35 the top guide plate.

11. In a safety removable hook fastener slide, a post having a vertical flat portion, a horizontal arrow shaped cam portion on an edge of said flat portion, a bottom rivet portion, a top 40

hook formed by a cut in the edge of said flat portion, a bottom trapezoidal guide plate for the hook fastener set against the bottom of said cam portion and formed with an opening set upon said rivet portion and rigidly held by said 5 rivet portion, a top trapezoidal guide plate for the hook fasteners and formed with a slot receiving said flat portion and set flat against the top of said cam portion and having curled portions set against the sides of said flat portion 10 and behind the cam portion, a pindle pin received within said curled portions and passing through the flat portion for pivotally connecting these parts, and a latch element swivelly mounted on said top guide plate and engageable 15 beneath said top hook to hold said top guide plate down against said cam portion, the swivelling of said latch element being accomplished with a rivet engaged therethrough and through 20 the top guide plate.

12. In a safety removable hook fastener slide, a post having a vertical flat portion, a horizontal arrow shaped cam portion on an edge of said flat portion, a bottom rivet portion, a top hook formed by a cut in the edge of said flat portion, a bottom trapezoidal guide plate for the hook fastener set against the bottom of said cam portion and formed with an opening set upon said rivet portion and rigidly held by 25 said rivet portion, a top trapezoidal guide plate 30 for the hook fasteners and formed with a slot receiving said flat portion and set flat against the top of said cam portion and having curled portions set against the sides of said flat portion 35 and behind the cam portion, a pindle pin received within said curled portions and passing through the flat portion for pivotally connecting these parts, and a latch element swivelly mounted on said top guide plate and engageable beneath said top hook to hold said top guide 40 plate down against said cam portion, the swivelling of said latch element being accomplished by a small extension engaged through an opening in the latch element, said extension being from a prong from the top guide plate, said prong serving as a stop to limit pivoting of the latch element.

BARNEY PRUZAN.
